UNITED STATES PATENT OFFICE.

HENRY B. LAHR, OF NEW YORK, N. Y., ASSIGNOR OF ONE-HALF TO BOWLING BALL COMPANY, OF NEW YORK, N. Y., A CORPORATION OF NEW YORK.

BOWLING-ALLEY.

No. 822,959.

Specification of Letters Patent.

Patented June 12, 1906.

Application filed February 18, 1904. Serial No. 194,164.

To all whom it may concern:

Be it known that I, HENRY B. LAHR, a citizen of the United States, and a resident of the borough of Manhattan, in the city and State of New York, have invented a new and useful Improvement in Bowling-Alleys, of which the following is a specification.

This invention relates to an improvement in bowling-alleys, and has particularly for its object to provide a new mechanism for insuring the accurate placing of the tenpins upon the bed of the alley.

A practical embodiment of my invention is represented in the accompanying drawings, in which—

Figure 1 represents in top plan such portions of a bowling-alley as will give a clear conception of the invention. Fig. 2 is a vertical longitudinal section through the same. Fig. 3 is an enlarged detail vertical section through the pin-bed and its adjacent parts for more clearly illustrating the means for raising and lowering the guide-pins, and Fig. 4 is a detail top plan view of the same.

It has always been extremely difficult to insure the accurate placing of the tenpins upon the spots on the pin-bed, such accurate placing being essential to the success of the game. This present invention is devoted to means for absolutely insuring this desirable accuracy, which means is constructed, arranged, and operated as follows:

The pin-bed is denoted by 1, the tenpins by 2, and the pin-spots marked by circles on the pin-bed by 3. A plurality of guide-pins 4 are fitted to slide through the pin-bed 3 around the periphery of each of the pin-spots, in the present instance three of such guide-pins being shown. The guide-pins 4 are also shown as sliding through the pin-bed 1 diagonally, so as to permit the bottom of the tenpin 2 to be placed upon the spot 3 between the said guide-pins. The bottoms of the guide-pins, which project below the bottom of the pin-bed 1, rest upon a plate 5, fitted to move vertically a limited distance toward and away from the pin-bed 1. In the present instance this plate 5 is provided with pillars 6 at its corners, which are guided into sockets 7 in the base of the alley.

When the plate 5 is raised, the tops of the guide-pins 4 are moved upwardly above the

top of the pin-bed 1, and when the plate 5 is lowered the guide-pins will be moved downwardly under the influence of retracting-springs 8, one for each pin, until the tops of the pins are flush with the surface of the pin-bed.

One or more racks 9 depend from the plate 5, and a cross-shaft 10 is provided with one or more pinions 11, meshing with said rack or racks. The shaft 10 extends transversely across beneath the pin-bed 1 and plate 5 and is mounted in suitable hangers 12. An operating-lever 13 is fixed to the shaft 10 and projects above the pin-bed 1, where it may be engaged by the person who sets up the pins. A bar 14 may be provided adjacent to the lever 13, which bar has a notch 15 therein, fitted to receive the usual latch 16, carried by the lever, for holding the lever in position to keep the plate 5 raised, and thereby the guide-pins 4 lifted above the surface of the pin-bed 1. This lever 13 may be operated by the bowler, when so desired, by means of a flexible connection 17, provided with a handle 18 near the delivery end of the alley, which flexible connection 17 passes around a pulley 19 and leads to the lever 13 at a point below the cross-shaft 10.

In operation when it is desired to set up the tenpins the lever 13 is rocked in a direction to raise the guide-pins 4 above the surface of the pin-bed. The tenpins may then be rapidly placed upon their spots, the guide-pins 4 serving to insure the accurate placing of the tenpins. After the tenpins have been set up the lever 13 is operated to permit the guide-pins 4 to drop flush with the surface of the pin-bed. If the bowler questions the accurate placing of the tenpins, he may grasp the handle 18, and thereby operate the lever 13 from the delivery end of the alley. If a tenpin has been misplaced, the raising of its guide-pins 4 will upset it.

It is evident that changes might be resorted to in the construction, form, and arrangement of the several parts without departing from the spirit and scope of my invention. Hence I do not wish to limit myself strictly to the structure herein set forth; but

What I claim is—

1. In a bowling-alley, a pin-bed and means for insuring the correct placing of the tenpins

thereon comprising a plurality of guide-pins arranged in groups on the pin-bed to slide diagonally toward and away from each other and means for raising the guide-pins above the surface of the pin-bed.

2. In a bowling-alley, a pin-bed, a group of diagonally-sliding guide-pins in the pin-bed for each tenpin, means for raising the guide-pins above the surface of the pin-bed, and springs engaging all of the guide-pins for

returning them to their normal position approximate to the surface of the pin-bed.

In testimony that I claim the foregoing as my invention I have signed my name, in presence of two witnesses, this 13th day of February, 1904.

HENRY B. LAHR
